LAMP BASE

Angelo Soriano, Brooklyn, N. Y.

Application May 3, 1938, Serial No. 205,664

4 Claims. (Cl. 242—85)

This invention relates to electric lamps and has particular reference to an improved lamp base which is constructed and arranged in such a manner as to house the extension cord therein and permit of the withdrawal therefrom of the required length to reach from the lamp to the outlet box.

The invention broadly comprehends a lamp base structure including relatively rotatable and axially movable members, one of which carries the lamp socket and a reel secured thereto and the other of which houses the reel and is provided with an opening through which the extension cord extends for effecting the winding and unwinding of the extension cord upon relative rotation of the members in opposite directions.

The invention further contemplates means for releasably locking the members of the lamp base structure against relative rotation when the desired length of extension cord has been wound upon or unwound from the reel.

As a further feature the invention embodies resilient means for disposing and maintaining the locking means out of engagement when the same is released so as to permit of free relative rotation of the lamp base members when winding up or unwinding the extension cord from the reel.

Other objects of the invention reside in the provision of an improved lamp base structure of the indicated character which is comparatively simple in its construction and mode of operation, inexpensive to produce and assemble and which is highly efficient for its intended purpose.

With the above enumerated and other objects in view, the invention is disclosed in greater detail in the following specification and the accompanying drawing in which:

Fig. 1 is a vertical sectional perspective view illustrating the relatively rotatable base members in locked relation.

Fig. 2 is a horizontal sectional view taken approximately on the line indicated at 2—2 of Fig. 1.

Fig. 3 is a similar view taken approximately on the line 3—3 of Fig. 1.

Referring to the drawing by characters of reference, the base includes relatively rotatable members designated generally by the reference characters A and B. The member A is composed of a foot 10 adapted to rest upon a supporting surface and provided with an upstanding central boss 11 which is provided with a socket 12 within which an upstanding pedestal section 13 is arranged.

The pedestal section 13 is preferably in the form of a solid rod, the upper end of which is externally threaded at 14 and has threadedly engaged therewith the upper end 15 of a downwardly flaring reel section 16, a set screw 17 serving to lock the reel section thereto. An upper tubular pedestal section 18 having an externally threaded lower end 19 is also threadedly engaged in the upper end portion 15 of the reel section 16 in spaced superposed relation to the pedestal section 13 and is locked by a set screw 20 against rotation with reference thereto. An upper reel section 21 is threadedly engaged over the threads 19 of the upper pedestal section 18 and is locked against rotation with reference thereto by a set screw 22.

The reel sections 16 and 21 flare in opposite directions and together define a reel upon which an extension cord C is adapted to be wound, the periphery of which is of arcuate concave formation which insures a substantially even winding of the convolutions of the cord thereon. The upper end of the pedestal section 18 has secured thereto a lamp socket 23 with which the wires of the extension cord are connected and from which the extension cord extends downwardly through the pedestal section 18 and outwardly through a radial opening 24 in the upper portion of the lower reel section 16.

The lower pedestal section 13 is secured within the socket 12 of the boss 11 of the foot 10 against rotary or axial movement by means of a plurality of radial studs 25 which are threaded through the boss 11 and have the inner pointed terminals 26 thereof engaging in depressions 27 formed in the pedestal section 13.

The upper portion of the boss 11 above the studs 25 is of reduced diameter to define a shoulder 28 the purpose of which will be herein-after set forth.

The member B of the base structure includes upper and lower mating hollow sections 30 and 31 which are removably secured together in any desired manner such as by the threaded connection 32 and the lower section is provided at its lower portion with a central bearing opening 33 through which the reduced upper end of the boss 11 extends. The upper section 30 of the member B is provided with a bearing opening 34 through which the upper section 18 of the pedestal extends so that the members A and B are associated with each other for relative rotation and for axial sliding movement between the shoulder 28 and the socket 23. The member B is provided with a radial aperture 35 through which the extension 55

cord C extends, the protruding portion thereof being provided with the usual plug 36 for connection with a current outlet socket. The member B is preferably provided with suitable handles 5 37.

Under this construction and arrangement it will be apparent that by lifting the lamp base structure and holding the same by the handles 37, the extension cord C may be pulled outwardly 10 to unwind the same from the reel, and conversely by turning the member A in the opposite direction with reference to the member B, the extension cord may be wound upon the reel. In this manner the required length of extension cord 15 may be withdrawn from the lamp base to reach from the current outlet socket to the lamp without exposing any undesirable slack in the cord and when the lamp is to be transported, the extension cord may be completely wound upon the 20 reel leaving only a short length thereof exposed. In order to provide means for locking the lamp base members A and B against relative rotation, a spring latch 40 is anchored as at 41 to the lower portion of the lower section 31 of the member B and said spring latch is provided with a keeper opening 42 which is adapted to selectively engage one of the radial studs 25. In order to dispose the latch 40 in a non-interfering position with the studs 25 when the latch is released, 25 a leaf spring 43 is anchored as at 44 to the member B and is provided with a bifurcated end 45 which straddles the reduced upper portion of the boss 11 and bears upon the shoulder 28 to exert a tension to effect a relative upward axial 30 movement of the member B with reference to the member A thereby disposing the spring latch out of the path of movement of the studs 25 to permit of free relative rotation of the members A and B. When the spring latch 40 is to be reengaged 35 with the studs 25, the member B is moved downwardly against the tension of the spring 43 until the keeper opening 42 registers with one of the studs.

What is claimed is:

45 1. A base for electric lamps including a pair of hollow nested members mounted for relative rotation and to slide axially relative to each other, a supporting foot at the lower end of one of said members, an extension cord reel intermediate the ends of said member, an extension cord extending downwardly from the upper end of said member and radially outward through the reel, the other member housing the reel and having a radial aperture through which the extension cord extends for winding and unwinding the cord on the reel when the members are relatively rotated, and interengageable means on said members for releasably locking the same against relative rotation, said means being engageable upon relative axial movement of said members in one direction and manually disengageable to permit of relative axial movement of the members in the

opposite direction and to permit of relative rotation thereof.

2. A base for electric lamps including a pair of hollow nested members mounted for relative rotation and to slide axially relative to each other, a supporting foot at the lower end of one of said members, an extension cord reel intermediate the ends of said member, an extension cord extending downwardly from the upper end of said member and radially outward through the reel, the other member housing the reel and having a radial aperture through which the extension cord extends for winding and unwinding of the cord on the reel when the members are relatively rotated, means provided respectively on said members engageable when the same are shifted axially with reference to each other in one direction for locking the members against rotation, and means for effecting relative axial movement of the members in the opposite direction when the locking means is released to dispose the same out of contact when winding and unwinding the extension cord. 20

3. In a base for electric lamps, a tubular pedestal member adapted to carry a lamp socket at its upper end and having a foot at its lower end adapted to rest upon a supporting surface, a reel secured to said pedestal intermediate the upper and lower ends, an extension cord leading through the pedestal from the upper end and outwardly through a radial opening in the reel, a hollow body mounted for rotation and limited axial sliding movement on said pedestal, enclosing said reel and having a radial opening through which the extension cord extends, and means 35 provided respectively on the pedestal and hollow body engageable upon axial sliding movement in one direction of the body on the pedestal to lock the body and pedestal against relative rotation and manually disengageable to permit of sliding 40 movement of the hollow body in the opposite direction upon the pedestal and to permit of relative rotation thereof.

4. In a base for electric lamps, a pedestal including a foot, a lower pedestal section extending upwardly therefrom, an upper tubular pedestal section in alignment therewith, a reel connecting said pedestal sections and disposed intermediate the length of the pedestal, and an extension cord extending from the upper end of the pedestal 50 through the upper section and outward through a radial opening in the reel between the upper and lower pedestal sections, a hollow body enclosing said reel and having a radial opening through which the extension cord extends, said 55 body being mounted upon the pedestal for relative rotation to effect winding and unwinding of the extension cord on the reel, and means for releasably locking said hollow body against relative rotation with reference to the pedestal. 60
